TURBINE SUPPORTING ARRANGEMENT

Glenn B. Warren, Niskayuna, N. Y., assignor to
General Electric Company, a corporation of
New York

Application June 25, 1938, Serial No. 215,808

10 Claims. (Cl. 60—95)

The present invention relates to elastic fluid turbines and more particularly to arrangements for supporting elastic fluid turbines used for propelling ships and the like.

Due to the expansion and contraction of the turbine elements during varying load conditions, it is necessary to provide supporting means which will allow expansion movements of the turbine casing in a manner so as to preclude undesirable stresses being set up in the turbine elements or the supporting framework. In installations where the turbine units are fast coupled to speed reducing gearing, it is necessary that the end of the turbine adjacent the gearing be fixed in a predetermined axial alignment with respect to the gearing. The supporting arrangement, however, must allow the end of the turbine remote from the gearing to expand in the axial direction and prevent the turbine from moving or shifting in the transverse direction out of such alignment.

It is an object of my invention to provide an improved construction and arrangement for supporting ship propulsion turbines and the like whereby they may expand and contract in the axial direction under varying conditions of operating temperature without creating undue stresses in the turbine or the connected elements.

It is a further object of my invention to provide a supporting arrangement for a ship propulsion turbine of high and low pressure units and an associated condenser which is simple in design having a relatively small number of structural members and accordingly of relatively light weight yet effective and efficient in operation.

For a better understanding of what I believe to be novel and my invention, attention is directed to the following description and the claims appended thereto taken in connection with the accompanying drawing.

In the drawing, Fig. 1 illustrates a side elevation of a turbine arrangement embodying my invention, Fig. 2 is an end view of the arrangement shown in Fig. 1, while Fig. 3 illustrates a modification of the invention.

The elastic fluid turbine comprises a high pressure unit 10 and a double flow low pressure unit 11 arranged axially parallel with respect to each other. Operating fluid is supplied to the high pressure unit through the inlet 12 and exhausts therefrom through the connection 13 to the low pressure unit. The rotors of the two turbine units are connected through shafts 14 and 15 to speed reducing gearing disposed within the hous-

ing 16 which transmits the power to the propeller shaft 18. The speed reducing gearing is mounted on suitable girders or ship framework members 17.

A condenser for condensing the exhaust elastic fluid from the low pressure turbine unit is disposed longitudinally parallel with and beneath the turbines, the vapor inlet thereof being directly connected with the exhaust casing 19 of the low pressure unit through the connection 20. The condenser may be of any well-known type such as of a water cooled type, as shown, which comprises a central drum section 21 and end sections 22 and 23. A plurality of tubes 24 secured in the tube sheets 25 and 26 extend longitudinally through the drum 21 and communicate with the end chambers. Cooling fluid, such as water, may be passed through the inlet 27, circulated through the tubes 24 and discharged through the outlet 28. Condensate may be drained from the condenser drum through the connection 29. In the preferred form of my invention, the tube sheet 25 in the left or fore-end of the condenser, as viewed in Fig. 1, is a relatively heavy and rigid plate having an extended area projecting beyond the sides of the drum which, in addition to its normal function of supporting the condenser tubes 24, also forms a part of the supporting arrangement for the turbine units as will be described.

The low pressure turbine exhaust casing 19 may be of any suitable form such as of the type shown in Patent 2,064,649, John H. Doran, and assigned to the General Electric Company. Such an exhaust casing is of a light weight and a compactly fabricated design. The exhaust casing is provided with extensions 30 for fixedly supporting the right or aft-end of the low pressure unit, as viewed in Fig. 1, in a predetermined axial alignment with the gearing. Although the aft-end of the turbine may be properly supported by different means, I prefer to provide the gearing housing with one or more suitable brackets as indicated at 31 to which the extensions 30 may be fastened. By this arrangement substantial savings in materials, weight and space are effected while at the same time relative movements between the turbine and the gearing may be more effectively precluded. The fore-end of the low pressure unit is secured to a flanged portion 32 of an upper extension of the condenser tube sheet 25. The lower portion of the tube sheet is also provided with flanged portions or feet 33 for fastening to the I-beam sections 34 which in turn are secured to the girders or other

framework members 35. The I-beam sections 34 are arranged so that the relatively thin and flexible webs thereof are parallel with the tube sheet 25 and perpendicular with respect to the axes of the turbine units. Thus, while the aft-end of the low pressure turbine unit is relatively rigidly and stationarily secured to the gearing housing, the fore-end of the turbine unit being supported upon the relatively flexible I-beam sections 34 may move in the axial direction in accordance with the operating conditions of temperature. Since the I-beam sections 34 are perpendicular to the axes of the turbine units, movements of the fore-ends of the turbine units 15 in a direction transverse to the axes thereof are effectively precluded.

The high pressure turbine unit 10 is also supported between the gearing housing and the condenser tube sheet 25 but independently of the low pressure unit and in a manner so that its structure may expand or contract independently of the other elements. As shown, the high pressure unit is suitably mounted upon a supporting frame 37, the aft-end of which is fixedly secured upon brackets 38 extending from the gearing housing and in a manner so that relative movements between this unit and the gearing are substantially precluded. The fore-end of the frame 37 is supported upon a flanged portion 39 of the tube sheet 25 through an intermediate relatively flexible plate 40, the plate 40 being arranged perpendicularly with respect to the axis of the high pressure turbine. Thus, while the aft-end of the high pressure turbine unit is relatively rigidly fixed, axial expansion movements of the turbine unit may take place by the flexing of the plate 40 between the frame 37 and the tube sheet 25.

While I have shown a supporting arrangement as adapted for a turbine comprising a pair of units, it is obvious that if a condensing turbine of a single unit is to be supported, the arrangement described in connection with the low pressure unit will be satisfactory. In Fig. 3 is illustrated a second modification of the invention in which the weight of the condensing turbine unit 11 is transmitted to the condenser structure through the rigid exhaust connection 29. In this arrangement it is understood that the drum 21 is of sufficient strength and rigidity for supporting the weight of the turbine. The extended tube sheet having the flanges 32 and 33, as described in connection with the first modification, may be dispensed with while the weight of the condenser and the superposed turbine is transmitted through any suitable means such as the brackets 42 to the relatively flexible I-beam sections 34.

Having described the principle of operation of my invention together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. In combination, a turbine, speed reducing gearing connected to said turbine, means for fixedly supporting the end of said turbine adjacent said gearing in a predetermined alignment therewith, a condenser disposed beneath said turbine and having an inlet rigidly connected with the exhaust casing thereof, said condenser having a relatively rigid transverse section adjacent one end thereof and secured to said turbine

for supporting the weight of the end of said turbine remote from said gearing, relatively flexible means arranged beneath said transverse condenser section for supporting the end of said condenser remote from said gearing so as to allow axial expansion movements of said condenser and said turbine relative to said gearing.

2. In combination, a turbine, driven means connected with the rotor of said turbine, means for fixedly supporting the end of said turbine adjacent said driven means in a predetermined alignment therewith, a condenser disposed beneath said turbine and having an inlet fixedly secured to the exhaust casing of said turbine, relatively rigid means including a portion of said condenser fastened to said turbine for supporting the weight of the end of said turbine remote from said driven means, means arranged beneath said condenser portion for supporting said condenser so as to allow expansion movements in the axial direction of said condenser and said turbine while preventing movements of said turbine and said condenser transversely to said axial direction.

3. In combination, a turbine, driven means connected to said turbine, means for fixedly supporting the end of said turbine adjacent said driven means in a predetermined alignment therewith, a longitudinal condenser disposed parallel with and beneath said turbine, means rigidly securing the inlet of said condenser with the exhaust casing of said turbine, said condenser having a tube sheet in the end thereof remote from said driven means, and transverse to the axis of said turbine, said tube sheet being rigidly connected to said turbine for supporting the weight of the end of said turbine remote from said driven means, means for supporting said condenser and said turbine including relatively flexible means arranged beneath said tube sheet permitting expansion movements of the condenser and said turbine with respect to said driven means only in the axial direction.

4. In combination, a turbine, speed reducing gearing connected to said turbine, means for supporting the end of said turbine adjacent said gearing rigidly upon the housing of said gearing, a condenser disposed beneath said turbine and rigidly connected with the exhaust casing of said turbine, means for rigidly supporting the end of said turbine remote from said gearing upon said condenser, flexible means arranged beneath said condenser for supporting the end of said condenser remote from said gearing so as to allow axial expansion movements of said condenser and said remote end of said turbine relative to said gearing, the end of said condenser adjacent said gearing being supported solely from said turbine.

5. In combination, a turbine, speed reducing gearing connected to said turbine, means for fixedly supporting the end of said turbine adjacent said gearing in a predetermined relationship with respect to said gearing, a longitudinal condenser disposed parallel with and beneath said turbine, means rigidly securing the inlet of said condenser with the exhaust casing of said turbine, said condenser having a transverse tube sheet in the end thereof remote from said gearing, means for rigidly securing the end of said turbine remote from said gearing to an extension of said condenser tube sheet, means for supporting said condenser and said remote end of said turbine comprising flexible means arranged beneath said tube sheet, said flexible means permitting expansion movements of said remote end of said turbine.

- with respect to said gearing only in the axial direction.
6. In combination, a turbine comprising a high pressure unit and a low pressure unit, speed reducing gearing connected to each of said turbine units, means for fixedly supporting the ends of said turbine units adjacent said gearing in a predetermined relationship with respect to said gearing, a condenser disposed beneath said turbine and secured to the exhaust casing of said low pressure unit, means including a relatively rigid cross-sectional portion of said condenser for supporting the ends of said turbine units remote from said gearing, means secured to the lower part of said condenser portion for supporting said condenser and said remote ends of said turbine units including means permitting expansion movements of said turbine relative to said gearing only in the axial direction.
7. In combination, a turbine comprising a high pressure unit and a low pressure unit, speed reducing gearing connected to each of said units, means for fixedly supporting the ends of said turbine units in a predetermined relationship with respect to said gearing, a longitudinal condenser disposed parallel with and beneath said turbine, the inlet thereof being secured to the exhaust casing of said low pressure unit, said condenser having a relatively rigid transverse tube sheet means for supporting the ends of said turbine units remote from said gearing upon said tube sheet of said condenser, means for supporting said tube sheet including flexible means arranged so as to permit expansion movements of the ends of said turbine units remote from said gearing only in an axial direction.
8. In combination, a turbine comprising a high pressure unit and a low pressure unit, speed reducing gearing connected to each of said units, means for fixedly supporting the ends of said turbine units adjacent said gearing in a predetermined relationship with respect to said gearing, a condenser connected to the exhaust casing of said low pressure unit, means for supporting

the end of said low pressure unit remote from said gearing on said condenser, means for flexibly supporting the end of said high pressure unit remote from said gearing on said condenser so as to allow axial expansion movements between said remote end of said high pressure unit and said condenser, means arranged beneath said condenser for supporting said condenser so as to allow axial expansion movements of said condenser and said remote ends of said units relative to said gearing.

9. In combination, a turbine, driven means connected to the rotor of said turbine, means for rigidly supporting the end of said turbine adjacent said driven means in a predetermined axial alignment therewith, a condenser, the exhaust casing of said turbine being rigidly connected to the upper portion of said condenser, the portion of said condenser remote from said driven means and adjacent the corresponding end of said turbine having a relatively rigid vertical section for supporting the weight of said corresponding turbine end, relatively flexible means arranged beneath said rigid condenser section for supporting said condenser so as to allow longitudinal expansion movements of said turbine with respect to said driven means.

10. In combination, a turbine, driven means connected to the rotor of said turbine, means for rigidly supporting the end of said turbine adjacent said driven means in a predetermined axial alignment therewith, a condenser arranged beneath said turbine and rigidly connected to the exhaust casing thereof, said condenser having a relatively rigid cross-sectional portion adjacent the end of the turbine remote from said driven means for supporting the weight of said remote turbine end, and means secured to the lower portion of said rigid condenser portion for supporting the condenser and the corresponding end of said turbine so as to allow only longitudinal expansion movements of said condenser and said turbine.

GLENN B. WARREN.
